CORE MOLD FOR WALLS

Vern E. Reichard, Stinnett, Tex.

Application November 8, 1944, Serial No. 562,500

5 Claims. (Cl. 25—128)

This invention relates generally to the class of plastic block and earthenware apparatus and pertains particularly to improvements in collapsible forms.

A principal object of the present invention is to provide a collapsible mold form designed to be used in the construction of walls, for the formation of air spaces or passages in the walls, which is constructed in a novel manner whereby it may be easily and quickly collapsed, after the wall forming material has set, for removal from the wall.

Another object of the invention is to provide a collapsible mold form designed to facilitate the formation of air spaces in concrete walls, which comprises a pair of spreader members which are used in association with collapsible end pieces to maintain the latter in an opened out condition, such spreader being so constructed that it may be easily and quickly reduced in width to facilitate the removal of adjacent parts of the form which it had maintained in position during the setting of the wall material.

Another object of the invention is to provide a collapsible mold form which is of relatively simple construction but which is strong and durable and which may be economically produced.

The invention will be best understood from a consideration of the following detailed description taken in connection with the accompanying drawing forming a part of the specification, with the understanding, however, that the invention is not confined to a strict conformity with the showing of the drawing but may be changed or modified so long as such changes or modifications mark no material departure from the salient features of the invention as expressed in the appended claims.

In the drawing:

Figure 1 is a view in top plan of a portion of a wall showing, in top plan, the core mold of the present invention installed therein.

Figure 2 is a sectional view taken substantially on the line 2—2 of Figure 1.

Figure 3 is a view looking at the end of one of the spreader members in opened condition.

Referring now more particularly to the drawing, the numeral 10 generally designates, in top plan, a cast or poured cement wall, the material for which is introduced between spaced outside form walls 11 which are commonly constructed of boards maintained in proper position by posts or studding 12.

In the construction of concrete walls it is common practice to form vertical openings or pas-

sages in the central part of the wall for ventilation to prevent penetration of moisture through from the outer side to the inner side of the wall. Various types of mold forms have been devised for the formation of such air passages, the majority of which are composed of a number of sections or parts and are more or less complicated and difficult to set up.

The device of the present invention is of simple construction and can be easily and quickly placed in position and maintained in such position until the cement for the wall has been poured.

In accordance with the present invention the core mold comprises a pair of spaced, parallel 15 relatively movable bars 13 each of which is formed longitudinally along one side to provide the substantially V-shaped rib 14 which is bordered at each side by a flat shoulder 15.

The adjacent sides of the bars 13 are centrally 20 longitudinally slotted as indicated at 16 and connecting the bars 13 together are the transverse flat links 17 which have their ends disposed in the slots of the bars and are secured to the bars by pivot pins 18 or other suitable means.

At the upper end of one bar 13 there is fixed 25 a rigid upstanding arm 19, the end of which is secured in the slot 16 of the adjacent bar.

Secured in the upper end of the slot of the bar adjacent the arm 19 is one end of a curved arm 30 20 which extends upwardly and is suitably curved to bridge the space between the bars 13, for connection by means of the bolt 21, with the arm 19, when the bars 13 are separated the necessary 35 distance. As will be readily apparent the coupling links 17 serve to maintain the bars 13 in proper spaced parallel relation.

As will be readily seen upon reference to Figure 1 the ribs 14 are oppositely directed. Co-acting with each of these ribs 14 is a spreader member which is generally designated 22 and which comprises two boards 23 each having a corner beveled off or chamfered as indicated at 24. These beveled surfaces 24 of the two boards making up the spreader are designed to be brought into opposing relation and the adjacent edges of the boards are pivotally coupled together by hinges 25. Thus the boards forming the spreaders 22 are coupled for relative movement and may be disposed in V formation.

50 The free longitudinal edges of the boards 23 are suitably formed as indicated at 26, to abut flat against the shoulders 15 so that each spreader member when in working position against the outer side of a bar 13, straddles the adjacent rib 14.

When the longitudinal edges or edge faces 26 of the spreader unit boards are disposed against the shoulders 15 so that the inner sides of the boards 23 bear against the face of the rib 14, the adjacent outer side of each board 23 will be disposed beyond the adjacent side of the bar 13. Thus when a side board 27 of the core mold is disposed in position at the sides of the bars 13, such board 27 will bear against the outer sides of the spreader boards 23 and will be spaced from the adjacent sides of the bars 13 as shown in Figure 1.

From the foregoing, it will be apparent that the outer side of the collapsible core mold is made up of the relatively wide side boards 27 and the V-shaped spreader members 22 which are interposed between the side boards 27 and are maintained in proper spaced relation by the interposed ribs 14 of the bars 13.

The bars 13 and the spreaders 22 will be of the same length and may be of substantial length to facilitate the casting or forming of a wall section of substantial height.

In setting up the wall form, the core mold parts are assembled in the relation in which they are shown in Figure 1 and a suitable number of wires are wrapped around the assembled parts as shown, such wires being designated 28. These wires hold the parts of the core together. The core is then set upright in position between the walls 11 and is secured in any suitable manner such as, for example, by disposing bars 29 across the top edges of the core boards 27 and the walls 11 as illustrated in broken lines in Figure 1. Such bars 29 may be scrap pieces of wood and maintained in place by driving nails 30 therethrough into the underlying edges of the walls and boards 27, as shown.

After the wall material has been poured and has set, the core mold is removed by taking out the bolt 21 connecting the arms 19 and 20. One of the bars 13 may then be shifted relative to the other so as to remove the separating ribs 14 from between the spaced or separated inner edges of the boards 23 of the spreader units 22. This will permit such units to be collapsed and when this is accomplished the side boards 27 of the core may then be separated from the wall and taken from the opening or passage 30 which has been formed in the wall.

From the foregoing description it will be readily apparent that the core form of the present invention is of relatively simple design and may be easily and quickly set up and removed from working position. At the same time it will be apparent

that the device may be constructed almost entirely from wood so that the use of valuable metal is to a great extent avoided.

I claim:

5. A core mold form of the character described, comprising a pair of relatively long, spaced, parallel members, a pair of units of substantially the same length as the members, designed to position against remote sides of the members, said units 10 being designed for adjustment as to width, means connecting each unit with a member for maintaining the unit at a predetermined width, means for coupling said members together for relative movement, and side boards designed to be positioned 15 upon opposite sides of the coupled members and to bridge the space between adjacent sides of the two units.
2. A core mold form, comprising two bar members arranged in spaced parallel relation, means 20 coupling such members together for relative parallel movement, a pair of spreader units designed to position against the remote sides of the bar members, said units each comprising two flat members hingedly coupled together along two 25 longitudinal edges for adjustment to the form in cross section, of a V, the opposite longitudinal edges being disposed against the adjacent bars, means carried by the bars for entrance between the flat members to maintain the adjacent edges thereof separated, a board overlying the bar members upon each side and engaging against the adjacent unit members, and means for securing the bar members in separated relation.
3. A core mold form as set forth in claim 2, in 30 which the said means carried by the bar members for entrance between the flat members, comprises an integral rib formed longitudinally of the remote faces of the bar members.
4. A core mold form as set forth in claim 2, in 35 which the thickness of the said opposite longitudinal edges of the flat members is such that the outer sides of such flat members will extend beyond the adjacent side faces of the bar members against which they abut, and said boards 40 lying against the outer sides of the flat members at the said opposite longitudinal edges thereof.
5. A core mold form as set forth in claim 2, in 45 which said bar members have their opposing faces each provided with a longitudinal slot, and the said coupling means comprises a series of link bars having their ends disposed in said slots, and pivot pins connecting the ends of the link bars with the bar members.
